US00D734879S

(12) **United States Design Patent**
Chen et al.

(10) **Patent No.:** US D734,879 S
(45) **Date of Patent:** ** Jul. 21, 2015

(54) **REFLECTIONAL LAMP**

(71) Applicant: **Zhejiang Shenghui Lighting Co., Ltd.**,
Jiaxing (CN)

(72) Inventors: **Liang Chen**, Jiaxing (CN); **Yudong Liang**, Jiaxing (CN); **Yinxiao Zhu**, Jiaxing (CN)

(73) Assignee: **Zhejiang Shenghui Lighting Co, Ltd.**,
Jiaxing (CN)

(**) Term: **14 Years**

(21) Appl. No.: **29/484,319**

(22) Filed: **Mar. 7, 2014**

(51) LOC (10) Cl. **26-04**

(52) U.S. Cl.

USPC **D26/2**

(58) **Field of Classification Search**

USPC D26/1-4; 313/313, 315, 316, 317, 318,
313/493; 315/52, 53, 56, 57, 58; 362/294,
362/373, 327

CPC B60Q 1/0064
